INVENTOR
Arthur Bates
By his Attorney,
Nelson N. Howard

UNITED STATES PATENT OFFICE.

ARTHUR BATES, OF LEICESTER, ENGLAND, ASSIGNOR, BY MESNE ASSIGNMENTS, TO UNITED SHOE MACHINERY CORPORATION, OF PATERSON, NEW JERSEY, A CORPORATION OF NEW JERSEY.

WAX-APPLYING DEVICE.

1,327,014.

Specification of Letters Patent.

Patented Jan. 6, 1920.

Application filed August 15, 1917. Serial No. 186,331.

To all whom it may concern:

Be it known that I, ARTHUR BATES, a subject of the King of England, residing at Leicester, Leicestershire, England, have invented certain Improvements in Wax-Applying Devices, of which the following description, in connection with the accompanying drawings, is a specification, like reference characters on the drawings indicating like parts in the several figures.

This invention relates to wax-applying devices adapted for use in the manufacture of footwear and is particularly concerned with the application of wax or like material in the course of finishing operations in the manufacture of footwear, as for example, the application of wax in the crease formed in a clog upper at the point where it is attached to the sole to cover the heads of the nails.

The general object of the invention is to provide a wax-applying device which may be readily brought into operative relation to the work and which will operate to apply a ribbon of wax upon the work quickly and neatly.

One feature of the invention consists in providing a wax-applying tool, having an elongated work-engaging surface which is shaped to co-act with the portion of work with which the tool is to be engaged, with a channel or furrow longitudinally of said work-engaging surface which shall assist in the formation of a ribbon or stripe of wax.

Another feature of the invention consists in arranging the wax-applying tool so that wax is supplied to its furrow at a point beyond the range of its engagement with the work in order to avoid interference with the free supply of wax.

Still other features whereby the operator is enabled to apply the work to the tool conveniently, the flow of wax controlled, and the desired flexibility obtained, will become clear from the following description of one specific form of the invention taken in connection with the accompanying drawings, in which,—

Figure 1 is a perspective view of a wax-applying device embodying features of the present invention in a preferred form;

Fig. 2 is a side elevation of parts of the

device shown in Fig. 1, but drawn to a scale larger than that of said figure; and

Fig. 3 is a front elevation of the applying tool hereinafter described, showing also part of a clog presented to the device for application of wax in the upper crease.

In the construction illustrated in the drawings, the device comprises an overhanging arm 2 adapted to be bolted to a support 1 and provided with a wax container 3 in which wax is maintained at the desired temperature by a gas flame from a burner 14. The nozzle 4 of the device is provided with a delivery passage 15 having a transverse branch 16 at its upper end which, as described in the specification of my Letters Patent No. 1,122,057, granted Dec. 22, 1914, is normally closed but is put into communication with the interior of the wax container 3 when the nozzle 4 is moved upwardly against the tension of a spring 17 in the presentation of the work to the device.

In the improved device, as shown, there is fixed to the lower extremity of the nozzle 4, by a screw 5, a work-engaging applying tool 6 bored to receive the nozzle 4 and roughly of oblong cross-section. The lower end of the tool 6 has a work-engaging surface preferably shaped to correspond to the portion of the work to which wax is to be applied and serving to assist in guiding the relative movement of the tool and work. For example, it may be beveled at 7 and 8 on both sides to give it a wedge-shape to fit more or less exactly the crease of a clog. The ridge so formed is rounded at the ends so that it is somewhat convex when viewed from one side, as shown in Fig. 2, the ridge 9 lying in a vertical plane and approximately at right angles to the axis of the nozzle. The ridge has a channel or furrow 9 running along its apex and at the upper end of the furrow there is an orifice 10 communicating with a duct bored in the block 6 to meet the delivery orifice of the passage 15 in the nozzle 4.

In using the device to deliver a continuous ribbon of wax into the crease of a clog to conceal the heads of the nails which attach the upper to the sole, the operator holding the clog in his hand presents it to the device so that the ridge or wedge end

of the tool 6 enters the crease. On pressing the work upwardly and with it the nozzle against the tension of the spring 17, wax 5 promptly commences to flow from the orifice 10 at the upper end of the channel or furrow 9 and filling the furrow flows into and is spread in the crease, and the operator using the ridged part of the block 6 as a crease guide runs the work along the tool 10 leaving a continuous ribbon of wax in the crease. The tool is preferably supported in an inclined position for the convenience of the operator and as a consequence of the disposition of the orifice 10 in the block 15 6 there is no tendency for it to become choked by extraneous matter which may be present on the work over which the tool passes. It is convenient to allow the tool 6 a certain amount of movement of accommodation with the nozzle 4 about the axis of the latter. To do this and yet limit the movement, it is convenient to fasten, as by a screw 12, to the nozzle guide chamber 20 above the nozzle an arm 11 projecting forwardly above the tool 6, a flat surface on the under side of which arm is just clear of a flat surface on the upper side of the tool, as shown in Fig. 2. In this way the tool 6 and nozzle 4 can rock or swivel a little 30 in either direction before being arrested by contact of the block with the arm 11.

Having thus described my invention, what I claim as new and desire to secure by Letters Patent of the United States is:

- 35 1. In a wax-applying device, a work-engaging tool having walls converging laterally from the sides of the tool to form an elongated work-engaging projection provided with a furrow extending longitudinally near the apex of said projection, and means for supplying wax to said furrow whereby with relative movement of the work and tool the wax is applied in a ribbon or stripe.
- 45 2. In a wax-applying device, a work-engaging tool having an elongated work-engaging surface constructed to enter a depression in the work with which the tool is to be engaged, a furrow extending longitudinally of said work-engaging surface opposite the bottom of the depression, and means for supplying wax to said furrow.
- 55 3. In a wax-applying device, a work-engaging tool having an elongated work-engaging surface shaped to correspond to the portion of the work with which the tool is to be engaged, a furrow running

longitudinally of said work engaging surface and extended to a point normally out of engagement with the work, and means for supplying wax to the portion of the furrow which is normally out of engagement with the work.

4. In a device for applying wax in a crease or groove in an article of footwear, an applying tool having a crease-entering ridge adapted to extend along the crease and within the same, said ridge being provided with a recess extending longitudinally of its apex to assist in the deposition of wax in the crease, and means for supplying wax to said recess.

5. In a device for applying wax to an article of footwear, an applying tool having an elongated work engaging surface, a furrow extending along said work engaging surface, said tool being supported so that the furrow is inclined to the horizontal, and means for supplying wax to the upper end of the furrow whereby the wax tends to flow along the furrow.

6. In a device for applying wax in a crease or groove in an article of footwear, an applying tool having an elongated wedge shaped work-engaging surface, a furrow along the apex of said wedge-shaped surface, said tool being supported so that the furrow is inclined to the horizontal, and means for supplying wax to the upper end of the furrow.

7. In a wax-applying device, a wax receptacle provided with an opening, an applying tool resiliently mounted to reciprocate in the opening and having a passage arranged to control the supply of wax by the movement of the tool relatively to the wax receptacle, said tool being provided with a work-engaging surface shaped to correspond to the surface of the work with which the tool is to be engaged, and a furrow extending along the work-engaging surface, said furrow being connected through the passage with said wax receptacle when the tool is moved by the application of the work thereto.

8. In a device for applying wax in a crease or groove, a wax receptacle, a wedge-shaped applying tool turning in said wax receptacle, and means for limiting the movement of the tool.

In testimony whereof I have signed my name to this specification.

ARTHUR BATES.
